EXPLOSIVE CHARGE

Robert L. Klotz, Conyngham, Pa., assignor to Seismograph Service Corporation, Tulsa, Okla., a corporation of Delaware

Application May 4, 1954, Serial No. 427,464

3 Claims. (Cl. 102—24)

The present invention relates to improvements in explosive charges and more particularly to improved explosive charge containers equipped with facilities for insuring complete detonation of a number of explosive cartridges when arranged in end-to-end relationship to form an elongated explosive column.

One method of insuring complete detonation of a long column of low sensitivity explosives of the type commonly used in mining, quarrying and similar operations, is described and claimed in co-pending application Serial No. 746,578, filed May 7, 1947, by Robert L. Klotz, Jr., and assigned to the same assignee as the present invention, which matured into Patent No. 2,683,414 on July 13, 1954. The above identified application discloses an arrangement wherein a plurality of cartridges, at least some of which have jet forming cavities in one end, are aligned in end-to-end relationship to form an explosive column of the desired length. When the column is detonated, the jet forming cavity in the end of each cartridge of the column which is so equipped produces an explosive jet which is directed into the next adjacent cartridge, thereby to strengthen and revitalize the detonating wave traveling along the column. The present invention relates to improved explosive charge containers for instrumenting the arrangement disclosed in the identified Klotz application in a simple and economical manner and for facilitating alignment of the cartridge containers in the desired end-to-end relationship in a shot hole.

It is an object of the present invention to provide an improved container assembly for explosive charges.

It is another object of the invention to provide explosive cartridges which are self-centering when stacked end-to-end to form a column.

It is a further object of the present invention to provide an improved container for explosive charges which is so formed and arranged that when two cartridges are stacked end-to-end they are self-centered and a jet forming cavity is provided in one end wall of one of the cartridge containers for producing an explosive jet upon detonation of the one cartridge which is directed into the adjacent end of the other cartridge.

According to a further object of the invention, one end wall of the present improved explosives container is provided with end wall parts defining an inwardly extending stand-off chamber which is adapted to be axially aligned with the jet forming cavity in the opposite end wall of an identical container when the two containers are arranged in end-to-end relationship.

In accordance with still another object of the invention, the present improved container is provided with exceedingly simple facilities for self-centering two or more stacked cartridges as they are placed one on top of the other, so that the jet forming cavity provided in one end of one cartridge container is automatically brought into registry with the stand-off cavity or chamber provided in the opposite end of the abutting cartridge container.

2

It is a still further object of the present invention to provide an improved elongated explosive charge made up of a plurality of self-centering cartridges and provided with jet forming cavities at spaced points along the charge which function to insure complete detonation of all of the explosive material in the charge.

Further objects and advantages of the present invention will become apparent as the following description proceeds, and the features of novelty which characterize the invention will be pointed out with particularity in the claims annexed to and forming a part of this specification.

For a better understanding of the present invention, reference may be had to the accompanying drawing, in which:

Fig. 1 is a view of a charge formed of a plurality of cartridges characterized by the features of the present invention and aligned in end-to-end relationship within a shot hole;

Fig. 2 is an enlarged sectional view taken along the line 2—2 in Fig. 1 showing one positional arrangement of the aligned cartridges;

Fig. 3 is a sectional view illustrating a modified embodiment of the present improved cartridge; and

Fig. 4 illustrates a modified embodiment of the present improved container structure.

Referring now to the drawing, and more particularly to Fig. 1 thereof, there is illustrated an explosive charge or column, generally designated by the reference numeral 10, and comprising a plurality of explosive cartridges 12 arranged in end-to-end relationship within a shot hole 11 drilled into the earth. In mining and quarrying operations, in particular, it is conventional practice to simply lower or push the cartridges 12 endwise into the shot hole 11 to form the column 10. The present improved cartridge is particularly well adapted for this type of handling, as will be apparent from the following description thereof.

It is well known that the detonation or propagation wave traversing a column of explosive material tends to become less intense the further the detonating wave travels from the point of initiation. This tendency increases as the diameter of the explosive column decreases. It also increases as the pressure, such as the fluid tamping pressure used in the shot hole increases, and as the sensitivity of the explosive material used is decreased. As a consequence, only a portion of the explosive material provided in a long column of low sensitivity explosive material may be exploded in response to detonation of the column at one end thereof. Moreover, when the column is sectionalized, as by stacking a number of cartridges in the manner described above, any foreign matter such as dirt, water, etc. which may inadvertently get between the ends of any pair of abutting cartridges, in many cases has the effect of attenuating the detonating wave as it travels from one cartridge to the abutting cartridge to the point where the abutting cartridge is not detonated. Any such undetonated explosive material used in a given charge is not only a waste of material, but, in addition, constitutes an explosives hazard which remains after the blasting or shooting operation is completed.

The problem outlined above is solved and the desired self-centering of the cartridges in the shot hole is obtained in a simple and economical manner by packaging the low sensitivity explosive material 13 in containers 14 characterized by the features of the present invention. Briefly and as best shown in Fig. 2 of the drawing, each container 14 is provided with wall parts which defined a conical jet forming cavity 14a in the explosive material disposed at the bottom of each cartridge, a conical jet forming cavity 20b in the explosive material disposed at the bottom of each cartridge, and a cylindrical stand-off

chamber 14b in the explosive material disposed at the top of each cartridge. More specifically, each container 14 comprises an elongated cylindrical body portion 15 having a cone-shaped bottom wall 16 integrally formed therewith and a top closure member 17. Many explosive cartridges presently sold commercially include a container 14 made of heavy cardboard or other material having relatively little strength. If the container 14 is comprised of such material, it may be difficult to maintain the desired conical shape of the bottom wall 16. Accordingly, if the container 14 is made of such material a metallic backing or liner plate 19 may be provided within the container 14. This plate is conically shaped to conform to the configuration of the bottom wall 16 and functions to reinforce the same.

The top closure member 17 has an end closure wall portion 17a of frusto-conical or convex configuration which matches the concave configuration of the end closure wall 16, so that the two end closure walls will seat in mating engagement when two or more cartridges are stacked in the manner illustrated in Figs. 1 and 2 of the drawing. In addition, the closure member is provided with a flange 17b which tightly embraces and may be adhesively secured to the rim of the container body portion 15 after the container body portion is filled with explosive material 13.

For the purpose of defining the stand-off chamber 14b in the explosive material 13 provided at the upper end of each cartridge, the end closure member 17 sealing the upper end of the cartridge is provided with a formed downwardly extending portion 20 located at the center of the closure member. This formed portion of the closure member is illustrated as being of generally cylindrical configuration and, as shown, is adapted to be aligned with the center of the end wall 16 in the adjacent abutting cartridge when two or more cartridges are stacked or otherwise arranged in end-to-end relationship. At its bottom end, the formed portion 20 is provided with a cone-shaped end wall 20a which defines the jet forming cavity 20b in the explosive material 13 disposed at the top of the container. As will be understood, the height of the stand-off chamber or well 14b defined by the formed wall portion 20 of the closure member 17 for each cartridge defines the stand-off distance between the two jet forming cavities 14a and 20b.

As will be evident from the above explanation with reference to Fig. 2 of the drawing, by making the end closure wall portion 17a of the end closure member 17 of frusto-conical configuration, the desired jet forming cavity 14a is formed between two stacked cartridges incident to the placing of the cartridges in end-to-end relationship. A second jet forming cavity 20b for producing an explosive jet effect in a direction opposite to the explosive jet produced by the cavity 14a is also provided between the two stacked cartridges incident to the placing of the cartridges in end-to-end relationship. These two jet forming cavities are separated by the stand-off chamber 14b. The concial configurations of the end closure walls 16 and 17a insure automatic alignment or centering of the cartridges as the cartridges are dropped into the shot hole 11 one on top of the other, or are successively lowered or pushed into a horizontally or vertically extending shot hole. Thus, if the uppermost cartridge of the column shown in Figs. 1 and 2 is lowered into the shot hole 11, this cartridge is automatically moved into vertical alignment with the other cartridges of the column through the camming action which occurs when the cone-shaped end closure wall 16 contacts the conical surfaces of the end closure member 17 forming a part of the next lower cartridge container. Since the engaged conical surfaces of the contacting end closure walls 16 and 17a are of mating configurations, the jet forming cavity 14a is confined to that area of the end closure wall 16 which is directly opposite or in registration with the stand-off cavity or chamber 14b in the

contacting end closure member 17. Moreover, the mating engagement of the contacting end closure walls serves to seal the cavities 14a and 14b formed between the walls against the entry of dirt and tamping fluid into these cavities during the charge tamping operation which is, of course, performed after the shot hole 11 is loaded with the charge 10.

As will be apparent from the above explanation, the purpose of providing the described container end wall configurations to define the cavities 14a and 20b when the cartridges are assembled into a column is to permit the well known "Munroe Effect," i. e., directionalized explosive effect, to be obtained. In other words, each cavity 14a or 20b acts to redistribute and concentrate the energy of the portion of the explosive material nearest the cavity. Each stand-off chamber 14b permits the explosive jet to form. More specifically, if the explosive column 10 is detonated from the top as seen in Fig. 1, the explosive forces developed at the surface of each cartridge container end wall 16 in registry with the cavity 14b of the next lower cartridge, meet at the axis of the cavity 14a within the cavity 14b of the next lower cartridge and add vectorially, thereby to effect concentration of explosive energy into a jet which is directed into the explosive material of the next lower cartridge. Alternatively, if the explosive column 10 is detonated from its bottom end, an upwardly directed explosive jet is produced by the jet forming cavity 20b in each cartridge, which is directed into the explosive material of the next higher cartridge. As a further alternative, if the explosive column 10 is detonated intermediate its ends, those jet forming cavities 14a which are disposed below the point of initial detonation are effective to produce downwardly directed explosive jets and those jet forming cavities 20b which are disposed above the point of initial detonation are effective to produce upwardly directed explosive jets.

In order to insure that the shapes of the end closure walls of each cartridge will be preserved, it is desirable to employ relatively rigid material, such as heavy cardboard or the like, in the construction of the end closure member 17 and the container body portion 15. In addition, the backing or liner plate 19 may be used, if desired, to insure preservation of the configuration of each end closure wall 16. As illustrated in Fig. 4 of the drawing, frangible sealing disks 21 and 22 may be adhesively secured to the end closure walls 16 and 17a of each container 14 to cover and seal the cavities 14a and 14b thereof against fluid entry into these cavities.

In use, the cartridges 12 are arranged in end-to-end relationship with the apexes of the cone-shaped cavities 14a pointing toward the point of detonation of the column thus formed. Thus when the cartridges are arranged in the manner shown in Fig. 1 with a detonating cap or fuse 23 located at the top of the column and connected to the fuse wires indicated at 24, the apexes of the cavities 14a in the cartridges 12 point upwardly toward the cap 23 and the apexes of the cavities 20b point downwardly. The cylindrically shaped cavity or chamber 14b in the top cartridge 12 of the column may be used to house the detonating cap 23. In such case, the cavities 14b are effective to produce the desired downwardly directed explosive jets from cartridge to cartridge in the manner explained above. However, under certain conditions it may be desirable to detonate the charge from the bottom, in which case the cavities 20b are effective to produce the desired upwardly directed explosive jets from cartridge to cartridge in the manner explained above. It will be understood that the column may also be detonated from an intermediate point. In such case and as explained above, toward the cap 23 regardless of its location in the column. Thus if the cap is disposed in the middle of the explosive column, then the cavities 20b above the detonating cap 23 are effective and the cavities 14a below the cap are effective.

In the modified embodiment of the invention illustrated in Fig. 3, the concave, convex end wall configurations are also utilized to obtain the above-described centering action as the cartridges 12 are arranged in end-to-end relationship. In this embodiment, however, the bottom end wall 116 is of convex configuration and the top closure member 117 is of concave configuration. The end closure member 117 of each container is provided with a downwardly extending rim for embracing the top of the cylindrical container walls 115. For the purpose of providing two oppositely directed jet forming cavities 114a and 116a having a stand-off chamber 114b therebetween in the explosive material contained within two abutting cartridges 12, a small hollow element 114 is provided in each container. This element, which may be formed of the same material as the container 14 or of any appropriate metal or plastic, has a cylindrical wall 114c defining the cylindrical stand-off chamber 114b and a cone-shaped top end wall 114d defining the jet forming cavity 114a in the explosive material contained within the container 14 in which the element 114 is provided. The element 114 is centrally disposed within the container 14 and the lower edge of the cylindrical wall 114c is adhesively or otherwise secured to the inner surface of the bottom end wall 116, so that the jet forming cavity 116a is formed by the central portion of the cone-shaped bottom end wall 116.

With the modified container arrangement illustrated in Fig. 3 of the drawing, the desired self-centering of the cartridges 12 as they are stacked is obtained through the coaction between the conical end closure walls 116 and 117 in a manner which will be clearly apparent from the above explanation with reference to the embodiment of the invention illustrated in Fig. 2 of the drawing. Also, the jet forming cavities 114a and 116a, and the stand-off chamber 114b function in the exact manner explained above with reference to the corresponding cavities 14a, 20b and 14b of the Fig. 2 embodiment of the invention. It will be understood, however, that in using the Fig. 3 embodiment of the invention, the jet forming cavity 116a is formed in the explosive material located at the top of each cartridge 12 as the bottom end wall 116 of another cartridge is seated on the top closure member 117 of the cartridge.

By employing the improved cartridge and container arrangements described above, a high intensity detonation jet is formed and directed from each cartridge into the next succeeding cartridge in the column which insures complete detonation of all explosive material in the column. Also by employing the present improved cartridges and containers, it is possible to use less sensitive explosives which are less expensive. Furthermore much longer columns may be detonated and propagation of the explosive effect is assured even where there is a substantial space between the cartridges, which space may be filled with air, water, mud, or the like.

It will be apparent to those skilled in the art that the present invention is not limited to the particular construction shown but that changes and modifications may be made without departing from the spirit and scope of the present invention. It is aimed in the appended claims to cover all such changes and modifications.

What is claimed as new and desired to be secured by Letters Patent of the United States is:

1. An explosive cartridge adapted for alignment with other identical cartridges to form an elongated column of explosives, comprising a container for explosive material, one end of said container being provided with a concave shaped end wall and the other end of said container being provided with a convex shaped end wall, the convex shaped end wall of said container being shaped and dimensioned to coact with the concave shaped end wall of an adjacent identical container to bring the two containers into axial alignment as the cartridges are assembled into a column, and structural means comprising

a liner extending inwardly of said first-named container from its convex shaped end wall and coacting with the concave shaped end wall of said adjacent container to define first and second spaced apart and oppositely directed jet forming cavities in the explosive material contained within the two containers, said liner defining a hollow standoff chamber extending axially of said first named container and having opposed ends one of which opens to the concave shaped end wall of said adjacent container so that the latter end wall cooperates with the liner to define said first jet forming cavity, said liner also being shaped to define said second jet forming cavity at the other end of and directed into said standoff chamber and extending into the explosive material in said first-named container.

2. An explosive cartridge adapted for alignment with other identical cartridges to form an elongated column of explosives, comprising a container for explosive material, one end of said container being provided with a concave, conically shaped end wall and the other end of said container being provided with a convex conically shaped end wall having the same cone angle as said concave shaped end wall, the convex shaped end wall of said container being shaped and dimensioned to coact with the concave shaped end wall of an adjacent identical container to bring the two containers into axial alignment as the cartridges are assembled into a column, and structural means comprising a liner extending inwardly of said first-named container from its convex shaped end wall and coacting with the concave shaped end wall of said adjacent container to define first and second spaced apart and oppositely directed jet forming cavities in the explosive material contained within the two containers, said liner defining a hollow standoff chamber extending axially of said first named container and having opposed ends one of which opens to the concave shaped end wall of said adjacent container so that the latter end wall cooperates with the liner to define said first jet forming cavity, said liner also being shaped to define said second jet forming cavity at the other end of and directed into said standoff chamber and extending into the explosive material in said first named container.

3. An explosive cartridge adapted for alignment with other identical cartridges to form an elongated column of explosives, comprising a substantially cylindrical container for explosive material, one end of said container being provided with a concave, conically shaped end wall and the other end of said container being provided with a convex conically shaped end wall having the same cone angle as said concave shaped end wall, the convex shaped end wall of said container being shaped and dimensioned to coact with the concave shaped end wall of an adjacent identical container to bring the two containers into axial alignment as the cartridges are assembled into a column, and structural means comprising a liner extending inwardly of said first-named container from its convex shaped end wall and coacting with the concave shaped end wall of adjacent container to define first and second spaced apart and oppositely directed jet forming cavities in the explosive material contained within the two containers, said liner defining a hollow cylindrical standoff chamber extending axially of and concentric with said first-named container, said chamber having opposed ends, one of which opens to the concave shaped end wall of said adjacent container so that the latter end wall cooperates with the liner to define said first jet forming cavity which is conically shaped and has its apex aligned with the axis of said chamber, said liner also having a conically shaped portion at the other end of said standoff chamber defining said second jet forming cavity which is directed into the standoff chamber and extends into the explosive material in said first-named container, the apex of said conically shaped liner portion being aligned with the axis of said standoff chamber and with

the apex of the concave shaped end wall of said adjacent container.
